Attorney.

UNITED STATES PATENT OFFICE.

ALEXANDRIA PROVOPULAS, OF FORT DODGE, IOWA.

DESIGN FOR A RING OR LOCKET.

52,857.

Specification for Design.

Patented Jan. 7, 1919.

Application filed May 22, 1918. Serial No. 236,062. Term of patent 3½ years.

To all whom it may concern:

Be it known that I, ALEXANDRIA PROVOPULAS, a citizen of the United States, residing at Fort Dodge, in the county of Webster and State of Iowa, have invented a new, original, and ornamental Design for Rings or Lockets, of which the following is a specification, reference being had to the accompanying drawing, forming part thereof.

Figure 1 is a top plan view, showing my new design; and

Fig. 2 is a side view thereof.

I claim:

The ornamental design for a ring or locket, as shown.

ALEXANDRIA PROVOPULAS.
